UNITED STATES PATENT OFFICE.

ARTHUR SIDWELL, OF WALTHAM, MASSACHUSETTS.

DESIGN FOR A TREAD-PIECE FOR BICYCLE-PEDALS.

SPECIFICATION forming part of Design No. 26,337, dated November 24, 1896.

Application filed October 12, 1896. Serial No. 608,659. Term of patent 14 years.

To all whom it may concern:

Be it known that I, ARTHUR SIDWELL, of Waltham, county of Middlesex, and State of Massachusetts, have invented and produced 5 a new and original Design for a Tread-Piece for Bicycle-Pedals, of which the following description, in connection with the accompanying drawings, is a specification, like letters on the drawings representing like parts.

10 Figure 1 is a perspective view of a tread-plate for bicycle-pedals embodying the design. Fig. 2 is a top plan view of the same, and Fig. 3 is a front elevation.

The tread-piece embodying the design is of 15 a general oval shape, the side portions *a* thereof being substantially straight and the end portions *b* curved from one of said side portions to the other to complete the oval.

15 The essential feature of the design consists 20 in the novel form of the horns or projections *b* from the end portions *b*, there being two of

such horns at each end of the pedal rising from the side portions and extending forward and converging toward each other. Each of the end portions is provided with two of such 25 horns diametrically opposite each other, so that on each side of the pedal there are two horns at opposite ends, but on the same side of the axis of the pedal. The said horns are curved, as shown, to conform to and overhang 30 the sole of a shoe.

I claim—

The design for a tread-piece for bicycle-pedals, substantially as herein shown and described.

35 In testimony whereof I have signed my name to this specification in the presence of two subscribing witnesses.

ARTHUR SIDWELL.
